SASHLESS WINDOW LATCH

Henry Reginald Baxter, P.O. Drawer 70, Abbotsford,
British Columbia, Canada

Filed Aug. 21, 1959, Ser. No. 57,244

Term of patent 14 years

(Cl. D50—5)

FIG. 1

FIG. 2

FIG. 3

FIG. 5

FIG. 4

FIG. 1 is a top plan view of a sashless window latch showing my new design;

FIG. 2 is a side elevational view of the latch;

FIG. 3 is a bottom plan view of the latch;

FIG. 4 is an end elevational view of the latch; and FIG. 5 is a perspective view of the latch on a reduced scale.

I claim:

The ornamental design for a sashless window latch, as shown.
